CLAIM

(57) The ornamental design for a parts washer, as shown and described.

DESCRIPTION

FIG. 1 is a perspective view of a parts washer shown in a closed configuration, in accordance with our invention; FIG. 2 is a top view of the parts washer of FIG. 1.

FIG. 3 is a bottom view of the parts washer of FIG. 1.

FIG. 4 is a right side view of the parts washer of FIG. 1.

FIG. 5 is a left side view of the parts washer of FIG. 1.

FIG. 6 is a back end view of the parts washer of FIG. 1.

FIG. 7 is a front end view of the parts washer of FIG. 1; and, FIG. 8 is a perspective view of the parts washer of FIG. 1 in an open configuration.

The broken lines shown in FIGS. 1-8 are for illustrative purposes only, and form no part of the claimed design.

1 Claim, 5 Drawing Sheets
